Inventor:
Natale D. Natale,

Conway J. R. Atty.

UNITED STATES PATENT OFFICE

NATALE D. NATALE, OF BANNING, PENNSYLVANIA

RAIL ANCHOR

Application filed May 2, 1928. Serial No. 274,567.

This invention relates to rail anchors of the type which have a clamping engagement with the base flanges of railroad rails and which cooperate with transverse ties 5 or other fixed abutments to prevent the rails from creeping longitudinally.

The main objects of the invention are to provide an improved one-piece rail anchor which may be easily clamped upon and removed from the base flange of a rail; which will be somewhat springy and yet heavy enough to be capable of withstanding excessive strains; which shall have a large contacting surface with a tie or other fixed abutment; and which will have means provided within one of its jaws for positively gripping the base flange of the rail.

Further objects of the invention, and the invention itself, will become apparent upon 20 a study of the following description when made in connection with the accompanying drawings which illustrate one form of my invention.

In the drawings:
25 Figure 1 shows a rail anchor in elevation, applied to a rail illustrated in section, the anchor being placed in abutting relation to a railroad tie.

Figure 2 illustrates a plan view of the 30 arrangement shown in Figure 1, the tread or upper portion of the rail having been removed.

Figure 3 is an end elevation of the anchor alone, as seen when looking toward 35 Figures 1 and 2 from the left.

Referring now to the various figures of the drawings, a rail 4 having a web 5 and base flange 6 is secured to cross ties 7 in the usual manner, as by spikes (not shown). 40 To prevent longitudinal creeping of the rail with respect to the tie 7, an anchor is provided for gripping the base flange 6 and abutting the tie 7, said anchor consisting of a single bar of metal having a jaw portion 8 for gripping the upper and lower 45 surfaces of one side of the base flange, a central portion 9, and an upwardly projecting shoulder 10 for abutting the other side of the base flange to hold the anchor in 50 place.

The anchor must be made of slightly flexible iron or steel in order that the strain upon the jaw 8 shall not be too great upon application of the anchor to the rail. To attach the anchor to the rail, one side of the 55 base flange is inserted within slot 12 and force or hammer blows are applied at the flat surface 11, which surface is perpendicular to the slot 12 of the jaw in order that the blows may be applied effectively and 60 without distorting the permanent shape of the anchor, and after the flange has been driven into slot 12 for a sufficient distance the shoulder 10 springs up into abutting engagement with the opposite side of the 65 flange.

The jaw 8 is made quite broad in order to give it great strength and to provide an extensive gripping surface between the horizontal sides of the slot 12 and the upper 70 and lower flange surfaces 13 and 14 which contact therewith. As it is unnecessary for shoulder 10 to be of such breadth as jaw 8, the anchor may be gradually inclined from the jaw to the shoulder by cutting it away 75 as by a vertical plane as indicated at 15. This not only reduces the amount of metal and therefore the cost of manufacture, but also increases the springiness and flexibility of the device.

The central portion 9 is dished out at 80 to further decrease the amount of metal, increase the resiliency, and to avoid improper engagement between the bottom of the rail flange and the anchor.

The vertical plane surface 18 which abuts the tie may be extended downwardly as at 85 19 to increase the contacting surface between the tie and anchor and thus absolutely prevent all tendency toward rocking or pivoting motion of the anchor. However, this portion 18 may be left off if desired, in which case a horizontal plane through line 20 would limit the lowest extremity of the anchor.

Even when the jaw 8 is driven tightly over flange 6 to provide frictional contact between the anchor and rail at 13 and 14, it has been found that there is still sometimes a slight tendency toward creeping. One of 100

the main features of the present invention lies in the provision of means for positively preventing this slight creeping action. A plurality of slots 21 (see Fig. 3), which 5 may be perpendicular to or slightly inclined from the perpendicular to the plane 11, are provided in the upper side of jaw 8. When the surface of the rail flange tends to move through main slot 12 a biting action thereon 10 results from pressure of the sharp edges of slots 21 against this surface and the flange is thus so tightly gripped that the rail cannot move. A similar group of slots might also be placed in the lower jaw portion.

15 Having now described my invention I wish it to be understood that various changes in the construction of my anchor may be made, which changes are to be limited only by the scope of the appended claims.

20 I claim:

1. A rail anchor comprising a broad jaw portion adapted to grip one side of the rail base, a plurality of slots substantially rectangular in cross-section within said jaw 25 portion, said slots being substantially perpendicular to the axis of the rail, a narrow flange portion for engaging the other side of the rail base, and an intermediate portion connecting said jaw portion and said 30 flange portion.

2. A rail anchor comprising a jaw portion for engaging one side of a rail base, spaced slots in said jaw portion substantially perpendicular to the axis of the rail, a 35 flange portion for engaging the vertical edge of the other side of the rail base, and an intermediate portion connecting said jaw portion and said flange portion, said intermediate portion comprising a continuous 40 substantially straight portion and a downwardly extending portion having a plane vertical surface, said downwardly extending portion being adapted to abut against a tie.

45 3. A rail anchor comprising a bar, formed at one end with a hook shaped jaw which projects over and grips the rail, spaced slots within said jaw substantially perpendicular to the axis of the rail, said bar being formed at the other end with a shoulder for engaging the opposite side of the rail base, and formed with an intermediate portion connecting the jaw with the shoulder.

50 In testimony whereof, I have hereunto set my signature.

55
